SET OF EDUCATIONAL BLOCKS

Margaret B. Fox, R.F.D. 3, Oakwood Road, Ames, Iowa

Filed Aug. 25, 1960, Ser. No. 61,886

Term of patent 14 years

(Cl. D34—15)

FIG. 1 is a top plan view of a set of educational blocks, showing my new design; and

FIG. 2 is a perspective view of one of the blocks of the set of FIG. 1, taken from the back of the block.

I claim:

The ornamental design for a set of educational blocks, substantially as shown.
